UNITED STATES PATENT OFFICE.

WILLIAM T. SMITH, OF PHILADELPHIA, PENNSYLVANIA.

DESIGN FOR A CHENILLE FABRIC.

SPECIFICATION forming part of Design No. 21,273, dated December 29, 1891.

Application filed December 4, 1891. Serial No. 414,058. Term of patent 3½ years.

To all whom it may concern:

Be it known that I, WILLIAM T. SMITH, a citizen of the United States, residing at Philadelphia, in the county of Philadelphia and State of Pennsylvania, have invented and produced a new and original Design for a Woven Chenille Fabric, of which the following is a specification, reference being had to the accompanying photographic print, making a part of this specification, and is sufficient to enable one skilled in the art of weav-

ing chenille fabrics to make and use my invention.

What I claim as my invention, and desire to secure by Letters Patent, is—

The design for a woven chenille fabric, consisting of the ornamentalations shown in the accompanying photographic print.

W. T. SMITH.
